SEAM-REDUCING MACHINE

John R. Oliver, Beverly, Mass., assignor to United Shoe Machinery Corporation, Borough of Flemington, N. J., a corporation of New Jersey

Application March 22, 1940, Serial No. 325,452

21 Claims. (Cl. 69—7)

This invention relates to machines for reducing the seams of articles of leather such as, for example, the back seams of shoe parts, and is illustrated as embodied in a machine for carrying out the method disclosed in Letters Patent of the United States 2,181,243 granted November 28, 1939, on the application of C. K. MacDonald. An object of the present invention is the provision of an improved machine for carrying out the method disclosed in this patent.

In the illustrated embodiment of the invention, the seam is reduced by passing it under a hot iron which is heated to a degree sufficient to sear and char the leather thus causing it to become slightly plastic, the leather being molded by the application of pressure to spread and flatten the seam. The seam becomes shrunken and compacted so that the surface of the treated edges is substantially bone hard. In accordance with one feature of the invention, the searing iron is formed with a series of ridges arranged in herringbone formation, the points of the ridges facing the entrance end of the iron, thus causing the edges of the seam ridge to be spread outwardly from one another. The ridges are spaced progressively nearer the work support from the entrance end of the iron to the exit end thereof so that the flattening of the seam ridge takes place progressively as the work is fed thereunder.

A further object of my invention is to secure positive and equal feeding of a work piece made up of two pieces of material joined by a seam so that the seam may be acted upon by a seam reducing means and so that the material will always be fed properly thereby regardless of variations in thickness of the work pieces or differences between adjacent pieces. This object is attained in accordance with a further feature of my invention by means of a lower feed roll for supporting the material and a pair of spaced driven upper feed rolls arranged to engage the work at opposite sides of a seam in the material. These upper feed rolls are yieldingly mounted for movement toward and away from the lower feed roll in accordance with the thickness of the work and are also capable of yielding movement relative to one another.

In accordance with a further feature of the invention, provision is made for directing the seam of the material to the searing iron. The searing iron is located between the upper feed rolls, and a gage is also located between these feed rolls and is arranged to engage the opposite sides of the seam ridge to direct the seam to the

iron. The gage and iron are also preferably mounted for yielding movement.

The lower feed roll is mounted at the outer end of an arm which extends laterally from and above the base of the machine. This lower feed roll is mounted for rotation about a horizontal axis which is substantially perpendicular to the longitudinal axis of the arm so that the machine may operate upon the back seam of closed uppers, such as those used in women's pumps, which may

be fed over the lower feed roll without interference from the frame of the machine. The upper feed rolls, the guide, and the searing iron which are all normally maintained adjacent to the lower feed roll are mounted on a head movable vertically upward to permit these members to be moved simultaneously away from the lower feed roll so that a plurality of closed uppers, the seams of which have been reduced and which have accumulated on the supporting arm, may be simultaneously removed on the machine without interference from the parts which cooperate with the lower feed roll. This arrangement forms a further feature of the invention.

In another aspect of the invention, the operating parts for reducing seams and which are located above the lower feed roll are arranged to be sequentially raised from the lower feed roll. The iron as illustrated is heated by a torch located above the iron with the flame thereof directed downwardly. This iron is arranged to be moved upwardly by the operator upon movement of a suitable controller such as a treadle, but to prevent the iron, when idle, from approaching too near the torch, the torch is first moved upwardly a considerable distance before the iron starts to move upward, whereupon the two members move as a unit. This movement of the iron permits removal of the iron from the work at any time during the passage of the work through the machine. If the operator desires to interrupt the feed of the work at any time, the feed rolls may be moved upwardly after the iron has been moved upwardly, by further depression of the treadle. If the treadle is still further depressed, the guide which engages the opposite sides of the seam ridge is moved upwardly thus facilitating removal of the work piece from the lower feed wheel before the work has passed entirely through the machine, if desired.

These and other features of the invention will now be described in the following detailed description and illustrated in the drawings wherein:

Fig. 1 is a side elevation of a machine in which the present invention is embodied;

Fig. 2 is a side elevation, on a larger scale, of the operating head of the machine, certain parts being shown in section;

Fig. 3 is a detail view partly in section illustrating the relative operating positions of the iron, the torch, and one of the upper feed wheels;

Fig. 4 is a plan view of the operating head of the machine;

Fig. 5 is a section on the line V—V of Fig. 1;

Fig. 6 is a section on the line VI—VI of Fig. 1;

Fig. 7 is a front elevation of the machine;

Fig. 8 is a vertical section on the line VIII—VIII of Fig. 6;

Fig. 9 is a detail view partly in section of the guide and its mounting;

Fig. 10 is a vertical section illustrating the mounting for the iron;

Fig. 11 is a front view on a large scale of the searing iron;

Fig. 12 is a perspective view of the iron illustrating the arrangement of the ridges in the bottom thereof;

Fig. 13 is a detail view, partly in vertical section along the seam, on a larger scale, of the iron, the guide for directing the work thereto, and the lower feed wheel, illustrating a piece of work being operated upon;

Figs. 14, 15, and 16 are vertical sections through the searing iron and the lower feed roll, illustrating the progressive reducing action of the iron upon the seam ridge; and

Fig. 17 is a view of a piece of work after the seam ridge has been reduced by the illustrated machine.

The machine is illustrated as being provided with a casing 10 supported on a base 12 (Fig. 1), the casing having a lower arm 14 extending laterally therefrom and an upper overhanging arm 16. A shaft 18 mounted within the casing 10 carries a pulley 20 at its outer end which may be connected by a belt 22 to a suitable driving means. The shaft 18 carries a worm 23 which engages a worm gear 24 mounted on the inner end of a shaft 26 journaled in the casing 10 and extending through the arm 14, the outer end of the shaft being journaled in the outer end of the arm. A bevel gear 28 is mounted on the outer end of the shaft 26 and engages a bevel gear 30 mounted on a shaft 32 which carries a lower feed roll 34 (Fig. 7). The shaft 32 is journaled at one end in a support 36 fastened to the outer end of the arm 14 by screws 38, this support being rounded to conform to the shape of the feed roll 34. The outer end of the arm 14 includes a rounded lateral extension 39 as shown in Fig. 1 to form a continuation of the support 36. A similar support 40 (Fig. 7) fastened to the outer end of the arm 14 at the opposite side of the roll 34 supports the other end of the shaft 32 and forms a housing for the gear 28. The supports 36 and 40 cooperate with the roll 34 to support a work piece such as a shoe upper which is to be fed by the roll 34 toward the inner end of the arm 14, during which time the back seam is to be reduced by mechanism to be described.

A pair of upper feed rolls 42 and 44 (Fig. 7) having serrated edges are arranged to engage a work piece at opposite sides of a seam therein. These rolls are individually yieldingly mounted to accommodate work pieces of different thicknesses and variations of thickness in a single work piece and these upper feed rolls are posi-

tively driven at equal speeds so that the work piece will be fed in a straight line by these feed rolls and the feed roll 34. The feed rolls 42 and 44 are mounted on shafts 46 and 48 respectively which are in turn mounted in the lower end of arms 50 and 52. These arms are pivoted on a shaft 54 secured in the lower end of a head 56 of the machine, which head is mounted for vertical movement in the outer end of the arm 16 (Fig. 5).

Gears 58 and 60 (Fig. 7) journaled on the shaft 54, engage gears 62 and 64 mounted on the shafts 46 and 48 respectively. Gears 66 and 68 mounted on a shaft 70 journaled in the head 56 of the machine mesh with the gears 58 and 60 respectively. The shaft 70 receives power through bevel gears 72 and 74 from a vertical shaft 76 journaled in the head 56 and having a spline connection at its upper end with a gear 78. The gear 78 is driven by a gear 80 mounted on the upper end of a downwardly and rearwardly inclined shaft 82 (Figs. 1 and 2) journaled in the outer end of the overhanging arm 16. The shaft 82 has a squared recess at its lower end (Fig. 1) which coacts with a correspondingly shaped recess in the upper end of a shaft 84, the lower end of which is journaled in the casing 10. The shafts 82 and 84 are maintained in driving engagement by a sleeve 86 pinned to the shaft 82, this sleeve permitting the shafts to move away from one another sufficiently to accommodate upward movement of the head 56 in the arm 16. The shaft 84 is connected to the driving shaft 18 by a worm gear 88 carried at the lower end of the shaft 84 and meshing with the worm 23.

Power is supplied to the feed rolls 42 and 44 by the gearing described above. Since there are separate sets of gearing between the shaft 70 (Fig. 7) and the individual feed rolls, and since these feed rolls are mounted for rocking movement about the axis of the shaft 54 carrying the gears 58 and 60, it will be seen that either of the upper feed rolls 42 and 44 may move upwardly relative to the other to accommodate variations in thickness of the work pieces or differences in the adjacent pieces.

The feed rolls 42 and 44 are normally urged downwardly toward the feed roll 34 under spring pressure. For this purpose the arms 50 and 52 which support the feed wheels have rearwardly extending portions 90 (Fig. 2) through which pass rods 92 which are supported for vertical movement in the head 56 and carry nuts 94 at the upper ends thereof. The lower ends of the rods 92 carry hemispherical members 96 which engage correspondingly shaped recesses in the extensions 90 of the arms 50 and 52, the lower sides of the members 96 being engaged by yieldable fingers 97 fixed to the arms. The rods 92 are urged upwardly to move the feed rolls 42 and 44 downwardly by springs 98 acting between the nuts 94 and a plate 100 fastened by screws 101 and 102 (Fig. 4) to the top of the head 56. This plate 100 has a rearward extension which overlies the forward end of the overhanging arm 16 to limit downward movement of the head 56 relative to the arm. A guard 105 also secured to the head 56 by a screw 107 encloses the bevel gears 78 and 80. Downward movements of the upper feed rolls are limited by screws 104 threaded into the under side of the head 56 and locked in adjusted positions by nuts 106. It will thus be seen that the springs 98 act through the rods 92 and the rearward extensions 90 of the arms 50 and

52 to urge the upper feed rolls toward the lower feed roll, while permitting individual upward movements of these rolls to accommodate varying thicknesses of material passing thereunder. The extent to which the upper feed rolls may move toward the lower feed roll may be varied by adjusting the screws 104. The shape of the head 56 is best illustrated in Fig. 5 wherein it will be seen that it is provided with a vertically extending dovetailed portion 160 received by a groove in the outer end of the arm 16 formed by the recess 112 and a gib 114 for permitting vertical movement of the head relative to the arm. The head 56 is illustrated in Fig. 2 as being in its lowermost position with the rear end of the plate 100 in engagement with the top of the arm 16. In order to move the head 56 upwardly and with it the various parts carried thereby, the machine is provided with an arm 116 (Figs. 1, 4, and 7) mounted on a shaft 120 journaled in the arm 16, this shaft also carrying a gear sector 122. The gear sector engages a gear 124 (Figs. 2 and 7) mounted on a shaft 125 which also carries a crank 126 the outer end of which is pivotally connected to a link 130 joined to the head 56 by a screw 132. The crank 126 and link 130 form a toggle connection which is straightened upon counterclockwise movement of the gear sector 122 and the consequent clockwise movement of the crank 126. This straightening of the toggle causes upward movement of the upper end of the link 130 thus causing upward movement of the head 56 relative to the arm 16 to lift the feed rolls 42 and 44 and the associated members to be described, upwardly from the feed roll 34 a considerable distance, thus permitting a plurality of vamps which have accumulated on the arm 14 to be removed simultaneously. The arm 116, by means of which the operator raises the head 56, is normally maintained in the position illustrated in the different views with the head 56 in its lowermost position, by a spring 134 connected at one end by a pin 136 fastened to the arm 116, the other end of the spring being connected to a pin 140 (Fig. 4) extending outwardly from the arm 16.

In order to guide the work with the seam ridge centrally disposed with respect to the upper feed rolls, a guide 142 is located therebetween and adjacent to the lower feed roll 34 (Figs. 2, 9, and 13). The guide has a slot 144 through which the seam of the work piece passes. This slot has walls that converge in the direction of feed of the work as indicated in Fig. 9 to facilitate entrance of the seam therein while closely embracing the seam ridge at the exit end of the guide to position the work accurately as it approaches a seam reducing iron to be described.

The guide 142 has an upwardly extending shank portion 146 which slides in an undercut groove 148 in the outer portion of the head 56 (Figs. 5 and 6). A screw 149 (Figs. 2 and 9) is provided at the top of the slide 146 and nuts 150 thereon engage the top surface of the head 56 to limit the downward movement of the guide. A spring 152 is seated on a lateral extension 154 of the shank 146, the upper end of the spring being seated within a recess 156 in the underside of the head 56 for urging the guide downwardly toward the lower feed roll 34 to the extent permitted by the nuts 150.

In order to reduce the seam ridge of the work, a searing iron 160 is positioned directly beyond the guide 142 in the direction of feed, this iron being in alignment with the groove in the bottom

of the guide. As indicated in Figs. 11 to 16 the iron is provided on its undersurface with a plurality of ridges 162 arranged in herringbone formation, the points of which are directed toward the entrance end of the iron to spread the material at each side of the seam outwardly. The iron is also provided with an entrance groove 164 and the ridges adjacent to this end of the iron are spaced further from the feed roll 34 than the ridges at the other end thereof to cause a progressive spreading and flattening of the seam ridge as it passes thereunder.

The iron is mounted in a slide 166 the lower end of which, as indicated in Figs. 3 and 13, is provided with a pair of vertical grooves for receiving upward legs 168 and 170 of the iron. Screws 172 and 174 secure the iron rigidly in place in the slide 166 and permit vertical adjustment of the iron with respect to the slide. The lower end of the slide is apertured to receive a torch 176 located above the iron 160 for heating the same. The slide 166 is mounted in a vertical dovetail groove 178 in the head 56 (Fig. 5), one wall of this groove being formed by an adjustable gib 180 secured in place by screws 182 and 183 (Figs. 2 and 5). A recess 184 (Figs. 2 and 10) is formed in the upper end of the slide and forms a seat for a spring 186 the upper end of which is received by a recess 188 formed in the plate 100 at the top of the head 56. This spring urges the iron downwardly toward the lower feed roll 34, this downward movement being adjustably limited by a screw 190 threaded into the top of the slide and the head of which bears against the upper surface of the plate 100.

The torch 176 is connected by a tube 192 (Fig. 8) to a mixing chamber 194 secured to a slide 196 mounted for vertical movement in a slideway 198 (Fig. 5). The mixing chamber is secured to the slide by a support 200 (Fig. 8) which is adjustably connected thereto by a screw 202 passing through an oversized hole in the lower end of the support 200 and threadedly received by the slide 196. The upper end of the support 200 is forked as indicated in Fig. 2 and embraces a pin 204 extending into the slide 196. Upon loosening the screw 202 the support 200 may be rocked about the axis of the pin 204 by reason of the oversized hole through which the screw 202 passes, thus permitting lateral adjustment of the torch 176 relative to the iron 160.

The torch 176 may be supplied with any suitable fuel which will give a sufficiently hot flame to raise the temperature of the iron to the desired value, one suitable fuel being a mixture of oxygen and acetylene. The mixing chamber 194 has a pair of inlets 210 and 212 to which are connected flexible tubes 214 and 216 respectively (Figs. 4 and 7) which are in turn connected to valves 218 and 220 (Fig. 1) which control the flow of gases through these tubes. These valves may be provided with indicia which cooperate with pointers 222 to indicate the relative amounts of gases being supplied through the tubes to the torch.

Provision is made for raising the various work engaging members carried by the head 56 relatively thereto. For this purpose a treadle rod 240 (Fig. 1) is arranged to be connected to a treadle and biased by means (not shown) to the position illustrated. The upper end of the treadle rod is pivoted to the outer end of an arm 242, the other end of which is fast to one end of a shaft 244 journaled in the housing 10. An arm 246 is carried by the other end of the shaft

244 and is pivoted to a link 248 which is in turn pivotally connected by a pin 249 to one arm 250 of a bell crank lever pivoted at 252 to an upwardly and rearwardly projecting arm 254 of the plate 100 secured to the top of the head 56. The other arm 255 of the bell crank lever is connected by a pin 284 to a link 256 the lower end of which is pivoted at 258 to the upper end of the torch slide 196. By depressing the treadle rod 240, clockwise movement is imparted to the bell crank lever which raises the torch slide 196 within the head 56 to move the torch away from the iron 160.

The iron 160 is arranged to be raised upon downward movement of the treadle rod 240, but not until the torch 176 has been moved upwardly a predetermined distance. For this purpose, a lost motion connection is provided between the arm 255 of the bell crank lever and the iron slide 166. This connection comprises a link 260 (Figs. 1, 2, and 10) pivoted at its upper end to an intermediate portion of the arm 255 of the bell crank lever, the lower end of the link 260 being provided with a slot 262 embracing a screw 264 projecting from the iron slide 166. As the arm 255 of the bell crank lever moves upwardly about the pivot 252, raising the torch 176, the link 260 is moved upwardly therewith and after the torch has been raised a sufficient distance the lower end of the slot 262 engages the screw 264 so that further upward movement of the arm 255 causes the iron to be lifted away from the lower feed roll 34.

Upon further downward movement of the treadle rod 240, the upper feed rolls 42 and 44 are arranged to be lifted. A pair of levers 270 and 272 (Fig. 4) are fulcrumed on a pin 274 mounted in the upper end of an arm 276 (Fig. 2) extending upwardly from the plate 100. The right ends of these levers are positioned over the upper ends of the rods 92, the upper ends of these rods being provided with rounded heads 278. Fingers 280 (Fig. 2) are secured by screws 282 to the underside of the levers 270 and 272 and engage the underside of the heads 278 so that the rods 92 move with the levers. The opposite ends of the levers 270 and 272 are positioned in the path of movement of the pin 284 which forms the connection between the bell crank lever arm 255 and the link 256, the pin having a portion 286 (Fig. 4) extending outwardly beyond the link 256. Upon upward movement of the arm 255 of the bell crank lever, after the iron has been lifted away from the lower feed roll 34, the extension 286 of the pin 284 engages the left ends of the levers 270 and 272 to rock these levers in a clockwise direction, thus forcing the rods 92 down against the action of the springs 90. This movement of the rods 92 causes the arms 50 and 52 supporting the feed rolls 42 and 44 to move clockwise, as viewed in Fig. 1, thus lifting the feed rolls away from the work.

During the raising of the torch, iron and feed rolls, the guide 142 has remained in its operative position. After the feed rolls start to move up by reason of the downward movement of the treadle rod 240, the guide 142 will be raised. This is accomplished by means of the engagement of a lug 290, secured by a screw 291 to the slide 146 (Fig. 2), with the bottom of a recess 292 formed in the side of the torch slide 196. This recess is made sufficiently long that the bottom thereof will not engage the lug 290 until the iron and feed rolls have been lifted.

In order to convey fumes resulting from the

searing of the material by the iron and charred bits of material removed thereby, away from the machine, the head 56 is provided with a vertically extending groove 300 (Fig. 5) which extends to the bottom thereof. The upper end of the groove 300 communicates with a passageway 302 extending through the overhanging arm 16 and being connected at the rearward end thereof with a pipe 304 (Fig. 1) which may be connected to a source of suction.

In operation, the parts of the machine will be in the positions illustrated in the drawings with the upper feed rolls 42 and 44, the guide 142, and the iron 160 adjacent to the lower feed roll 34. Assuming the back seam of a closed upper U is to be reduced the upper is presented inside out to the machine with the heel portion supported on the feed roll 34 and the supports 36 and 40, and with the seam ridge entering the slot in the guide 142. This slot guides the seam ridge and centers it with respect to the iron 160 to which the seam passes, the feeding action being effected by the cooperative action of the upper and lower feed rolls. During its passage under the iron, the ridges 162 which are arranged in herringbone formation spread the same ridge and progressively flatten it as indicated in Figs. 14 to 17, due to the fact that the ridges in the lower surface of the iron are progressively nearer the adjacent surface of the feed roll 34. The iron is heated by the torch 176 to a sufficiently high temperature to cause the leather to be charred and rendered slightly plastic, this action causing the seam to become shrunken and compacted and rendering the surface of the treated edges substantially bone hard. In addition to spreading and flattening the seam ridge, the ridges 162 also act to remove charred portions of the material, the finished reduced seam S having the general appearance shown in Fig. 17.

After the seam ridge has been reduced, the upper U moves on to the lower arm 14 (Fig. 1) and another upper may be passed through the machine. The uppers collect on the arm 14 as indicated in Fig. 1 wherein is illustrated two uppers which have been passed through the machine. The arm 14 has capacity for collecting a large number of uppers and in order to permit simultaneous removal thereof, the head 56 and all the operating parts carried thereby may be raised a considerable distance by moving the arm 116 downwardly thus effecting a straightening of the toggle composed of the crank arm 126 and link 130.

Should the iron become too hot or should it be desired to raise the iron away from the work, the torch is first lifted away from the iron by depressing the treadle rod 240. Thus, at the will of the operator the iron may be rendered ineffective at any time and the torch will always be spaced sufficiently therefrom to prevent overheating of the iron. Should the operator desire to interrupt the feeding movement of the work, the treadle rod 240 is further depressed which raises the upper feed rolls 42 and 44 out of engagement with the work, and if the operator desires to remove the work piece before it has passed through the machine, further depression of the treadle rod 240 will raise the guide 142 to facilitate this removal.

Having thus described my invention, what I claim as new and desire to secure by Letters Patent of the United States is:

1. In a seam-reducing machine, a lower driven feed roll for supporting a piece of work, a pair

of spaced, upper, driven feed rolls coacting with said first roll for engaging the other side of the work on opposite sides of a seam therein, and seam-reducing means between said upper feed rolls.

2. In a seam-reducing machine, a lower driven feed roll for supporting a piece of work, a pair of upper driven feed rolls coacting with said first roll for engaging the other side of the work on opposite sides of a seam therein, means mounting said upper feed rolls for yielding movement, and seam-reducing means located between said upper feed rolls.

3. In a seam-reducing machine, a lower driven feed roll on which a work piece may be supported, a pair of spaced upper driven feed rolls coacting with said first roll for engaging the upper side of the work on opposite sides of a seam therein, means mounting said feed rolls for independent yielding movement, and seam-reducing means associated therewith.

4. In a back-seam-reducing machine, a supporting arm, a lower driven feed roll mounted at the end of said arm and arranged to rotate about a horizontal axis substantially at right angles to the axis of said arm, a pair of upper driven feed rolls arranged to engage a work piece supported on said lower feed roll at opposite sides of a seam therein, and seam-reducing means associated with said upper feed rolls.

5. In a seam-reducing machine, a lower driven feed roll, a pair of upper driven feed rolls arranged to engage a work piece supported on said lower feed roll at opposite sides of a seam therein, means for moving said upper feed rolls away from said lower feed roll, and seam-reducing means arranged to act on the seam of the work piece.

6. In a seam-reducing machine, a lower driven feed roll, a pair of upper driven feed rolls arranged to engage a work piece supported on the lower feed roll at opposite sides of a seam therein, seam reducing means located between said upper feed rolls, and guide means engaging said seam and directing it to said seam-reducing means.

7. In a seam-reducing machine, coacting feed rolls arranged to grip opposite sides of a work piece therebetween, seam-reducing means associated with said feed rolls for reducing a seam in the work piece during feeding movement thereof, and guide means engaging opposite sides of said seam and arranged to direct the work to said feed rolls with the seam properly disposed with respect to said seam-reducing means.

8. In a seam-reducing machine, a lower driven feed roll, a pair of upper feed rolls arranged to engage a work piece supported on the lower feed roll at opposite sides of a seam therein, a yieldingly mounted searing tool between said upper feed rolls, and guide means arranged to engage the seam and direct it to said searing tool.

9. In a seam-reducing machine, a lower feed roll, a pair of upper feed rolls arranged to engage a work piece supported on said lower feed roll at opposite sides of a seam therein, a yieldingly mounted searing tool between said upper feed rolls arranged to reduce the seam, guide means for directing the seam of the work piece to said searing tool, and means for raising said guide means and said searing tool away from the lower feed roll.

10. In a seam-reducing machine, a lower driven feed roll, an upper driven feed roll arranged to

engage a work piece supported on the lower feed roll adjacent to a seam therein, a searing tool adjacent to said upper feed roll for reducing the seam of the work piece, a guide engaging the seam and arranged to direct the work piece to the searing tool, means for raising in a predetermined sequence said searing tool, said upper feed roll, and said guide, and additional means for simultaneously raising the searing tool, upper feed roll and guide.

11. In a seam-reducing machine, a pair of spaced feed rolls arranged to engage a work piece at opposite sides of a seam therein, a searing tool located between said feed rolls and beneath which the seam of the material is directed to be reduced thereby, and a guide for directing the material with the seam passing centrally beneath said searing tool.

12. In a seam-reducing machine, means for feeding a work piece having a seam therein to be reduced, a searing tool arranged to engage the seam ridge, said searing tool having a ridge-receiving entrance groove, and a guide arranged to engage opposite sides of the seam ridge for directing the seam ridge to said entrance groove.

13. In a seam-reducing machine, a work support, means for feeding material having a seam ridge to be reduced, a searing tool arranged to engage the seam ridge, said tool having a ridge-receiving entrance groove and seam-engaging ridges beyond said groove in the direction of feeding movement, and a guide for directing the seam ridge to said entrance groove.

14. In a seam-reducing machine, means for feeding a work piece having a seam ridge to be reduced, a searing tool having an entrance groove for the seam ridge, and seam-engaging ridges beyond said groove in the direction of feeding movement, said ridges being arranged substantially in herring-bone formation with the ridges diverging in the direction of feeding movement.

15. In a seam-reducing machine, means for feeding a work piece having a seam ridge to be reduced, a searing tool having an entrance groove for the seam ridge, and seam-engaging ridges beyond said groove in the direction of feeding movement, said ridges being arranged substantially in herringbone formation with the ridges diverging in the direction of feeding movement, said ridges approaching closer to the body of the material at the exit end of the searing tool than adjacent to the entrance groove.

16. In a seam-reducing machine, a work support, means for feeding a work piece having a seam ridge therein over said work support, a searing tool arranged to engage said seam ridge for reducing the same, said searing tool having work engaging ridges arranged substantially in herringbone formation.

17. In a seam-reducing machine, a work support, means for feeding a work piece having a seam ridge therein over said work support, a searing tool arranged to engage said seam ridge for reducing the same, said searing tool having work engaging ridges arranged substantially in herringbone formation, said ridges being arranged progressively nearer the work support from the entrance end thereof to the exit end thereof.

18. In a seam-reducing machine, a work support, means for feeding a work piece having a seam ridge therein over said work support, a searing tool arranged to engage said seam ridge for reducing the same, said searing tool having work engaging ridges arranged substantially in herringbone formation, and a guide engaging

opposite sides of said seam ridge and arranged to direct the same to the center of said searing tool.

19. In a seam-reducing machine, means for supporting a work piece having a seam therein, an iron located above the supporting means for engagement with the seam, a torch mounted above the iron for directing a flame thereon, and operator controlled means arranged upon initial movement thereof to raise the torch away from the iron, and upon further movement thereof to raise the iron away from the work piece.

20. In a seam-reducing machine, a lower feed roll for supporting a work piece, an upper feed roll cooperating therewith to feed the work, a searing iron adjacent to the upper feed roll and arranged to engage a seam ridge in said work piece, a torch mounted above the iron and arranged to direct a flame downwardly thereon, a

guide adjacent to said feed roll and arranged to direct the seam to said iron, and means for progressively raising the torch, the iron, the feed roll and the guide in the order named.

5 21. In a seam-reducing machine, a lower feed roll for supporting a work piece, an upper feed roll cooperating therewith to feed the work, a searing iron adjacent to the upper feed roll and arranged to engage a seam ridge in said work piece, a torch mounted above the iron and arranged to direct a flame downwardly thereon, a guide adjacent to said feed roll and arranged to direct the seam to said iron, means for progressively raising the torch, the iron, the feed roll and the guide in the order named, and additional means for simultaneously raising said torch, iron, feed roll and guide.

JOHN R. OLIVER.
